COMBINATION PICTURE HANGER AND CURTAIN TIE-BACK

Original Filed April 28, 1936

UNITED STATES PATENT OFFICE

2,396,350

COMBINATION PICTURE HANGER AND CURTAIN TIEBACK

Harry Tashman, New York, N. Y.

Substituted for abandoned application Serial No. 76,718, April 28, 1936. This application May 23, 1944, Serial No. 536,979.

2 Claims. (Cl. 248—29)

This invention relates to combination picture hangers and curtain tie-backs and the like articles.

An object of this invention is to provide an article of the character described for hanging pictures or mirrors, which may be used with or without a molding, the construction being such that the hanger may be nailed to the wall even when used with a molding.

Another object of this invention is to provide an article of the character described which may be used as a tieback for curtains or drapes and when used as such may be fastened to a wall.

Still another object of this invention is to provide a neat and durable article of the character described which shall be relatively inexpensive to manufacture, easy to apply, attractive in appearance, and withal practical and efficient to a high degree in use.

Other objects of this invention will in part be obvious and in part hereinafter pointed out.

The invention accordingly consists in the features of construction, combinations of elements, and arrangement of parts which will be exemplified in the construction hereinafter described and of which the scope of application will be indicated in the following claims.

In the accompanying drawing, in which is shown one of the various possible illustrative embodiments of this invention,

Fig. 1 is an elevational, cross-sectional view of an article embodying the invention when used as a picture hanger;

Fig. 2 is a rear elevational view of my improved article;

Fig. 3 is a horizontal cross-sectional view of a wall provided with a tieback embodying the invention;

Fig. 4 is a view similar to Fig. 3, but illustrating the tieback fastened to the wall;

Fig. 5 is a perspective view of my improved article and illustrates a modified form thereof; and

Fig. 6 is a perspective view of another modified form of the invention.

Referring now in detail to the drawing, 10 designates an article embodying the invention, here shown in the form of a combination picture hanger and tieback. The article 10 comprises a member 11 made of a single blank of sheet metal having a flat intermediate portion 12 formed with a central opening 12a, and a rolled over portion 13 extending from the upper end of said first portion. Said portion 13 is substantially of semi-cylindrical shape, terminating in an end edge 14; and is formed with a substantial

square opening 15 having side edges 16 parallel to the side edges 17 of said portion and edges 18 parallel to said end edge. Extending from the edge 18 adjacent said end edge 14, is an upwardly and outwardly inclined tab 20 cut from the material of the opening 15. Said tab is preferably inclined away from the portion 12 of member 11, and has an opening 21 to receive a nail 22 or the like fastening member.

Extending from the lower end of said portion 12 is a downwardly and outwardly inclined flat portion 25 extending to the same side of portion 12 as portion 13. Said inclined portion 25 is formed with a pair of spaced openings or cut away portions 26 for the purpose hereinafter appearing. The outer edge 27 of said portion 25 is parallel to edge 14 of portion 13, and a plane passing through said outer edge and parallel to said portion 12 substantially passes through the center of curvature of the curved portion 13. The openings 26 may be replaced by notches in the side edges of portion 25.

Attached to member 11 is a rosette or ornament 30 of any suitable kind having a stud screw 31 projecting through the opening 12a and being fastened to portion 12 of said member by a nut 32 on said screw.

When using the article 10 as a picture or mirror hanger, the same may be hung on a molding 35 with the curved portion 13 engaging the top bead 36 thereof. A nail 22 may be driven through opening 21 into the wall 37. The lower edge 25 contacts the bottom of the molding.

A cord 40 supporting the picture or mirror 41 is looped through the openings 26 and over the strip of metal 42 separating said openings. The space between the portion 25 and the rosette 30 accommodates the portions of the cord passing downwardly through said openings.

Figs. 3 and 4 illustrate the article 10 as a tieback. As shown in Fig. 3, the cord passes through openings 26 and 15, and is looped about the curtains or drapes 45 and attached to a hook 47 screwed to the wall.

As shown in Fig. 4, the tab 20 is engaged with one hook 50 and the cord 40 is looped through openings 26 and around strip 42, the outer end being attached to another hook 51. Instead of hook 50, a nail may be driven through the opening 21 for fastening the tieback to the wall.

In Fig. 6, there is shown a combination hanger and tieback 10a, illustrating a modified construction. The device 10a comprises a member 11a attached to a rosette 30a. The member 11a is in the form of an open frame and has a counter-

part for each part of member 11, as will appear hereinafter. Said member 11 comprises a part 54 made of suitably shaped wire stock having parallel straight portions 55 from which extend similar, curved, semi-circular portions 56 interconnected by a portion 57 parallel to the plane of said straight portions. Extending from said straight portions 55 are similar parallel portions 58 inclined to the plane of said straight portions, terminating in inwardly looped, contacting eyelets 59. The straight portions 55 are interconnected by a cross strip 60 soldered or welded thereto and having a central opening 61. A cross piece 62 interconnects the curved portion 56 and is soldered or welded thereto. A small U-shaped loop 63 is soldered or welded to portion 57 of member 54, forming an eyelet therewith.

It will now be understood that the member 11 functions in a manner similar to member 11a. A nail or fastening member may be driven through loop 63. The member may be hooked on a molding. The cord may be looped through the eyelets 59 and passed between portion 57 and cross piece 62. The rosette may be screwed to cross piece 60 through opening 61.

In Fig. 5, there is shown a member 11b similar to member 11, except that the former has notches 70 in the sides of the curved portion thereof to receive the cord 40. Furthermore, there is hinged to the bottom of the inclined portion as at 71, a wire hook 72 adapted to receive a nail or other fastening means for fastening the hanger to the wall. The hook 72 may be swung against the inner side of said member 11.

It will thus be seen that there is provided a device in which the several objects of this invention are achieved, and which is well adapted to meet the conditions of practical use.

As various possible embodiments might be made

of the above invention, and as various changes might be made in the embodiments above set forth, it is to be understood that all matter herein set forth or shown in the accompanying drawing is to be interpreted as illustrative and not in a limiting sense.

Having thus described my invention, I claim as new and desire to secure by Letters Patent:

1. An article of manufacture comprising a member having an intermediate portion, an upper curved portion at one end of said intermediate portion adapted to hookingly engage a molding on a wall, and a lower portion at the other end of said intermediate portion extending from the plane thereof to the same side as said curved portion and adapted to contact said molding, and a tab extending from said curved portion adjacent the end of said curved portion, and bent upwardly away from said curved portion and having an opening to receive a nail, adapted to be driven into the wall.

2. An article of manufacture comprising a member having an intermediate portion, an upper curved portion at one end of said intermediate portion adapted to hookingly engage a molding on a wall, and a lower portion at the other end of said intermediate portion extending from the plane thereof to the same side as said curved portion and adapted to contact said molding, and a tab extending from said curved portion adjacent the end of said curved portion, and bent upwardly away from said curved portion and having an opening to receive a nail, said lower portion having an opening to receive a cord, and said upper curved portion having an opening, and said tab extending from one end of said last-mentioned opening.

HARRY TASHMAN.
